SIGN SUPPORT

Floyd R. Perkins, Chicago, Ill.

Application April 26, 1935, Serial No. 18,315

3 Claims. (Cl. 248—230)

This present invention has to do with a sign and sign support. The invention relates particularly to a device suitable for supporting a sign upon a bottle or the like for animation 5 manually or from currents of air.

The objects of the invention, among others, include the provision of the following:

An improved simple and effective support for a sign that is adapted to rotate in the breeze. 10 An improved combination of support for a sign and a sign therein whereby the sign may be exposed to the drafts or currents of air in a store or elsewhere and thus be animated.

An unique combination with a bottle or other 15 container, of a standard for a sign, a sign, and means for suspending such sign that it will be animated by the slightest draft of air.

These objects, and such other objects as may 20 hereinafter appear, are obtained by the novel construction, unique combination, and improved arrangement of the several elements constituting the invention, one form of which is illustrated in the accompanying drawing, hereby made a part of this application, and in which 25 the figure is a perspective of a sign, a support therefor, and a fragmentary portion of a bottle upon which such standard is secured.

Like reference characters are used to designate similar parts in the drawing and in the 30 following description.

In the figure, a bottle 10 of conventional type is shown. The bottle 10 has a constricted neck 11 which is surrounded by a flange 12. A standard 13 is supported about the constricted neck 35 11 adjacent the flange 12.

The standard 13 comprises an upright or vertical section 14, a horizontal lower section 15 integral with section 14, a substantially circular section 16 integral with section 15, an extension 40 17 from the substantially circular portion 16, a second and upper horizontal section 18 integral with section 14, and a hook section 19 at the end of and integral with section 18. The entire support except a locking ring used therewith may 45 be a single strand of wire suitably bent or shaped.

The standard 13 is secured upon the neck 11 by encircling such bottle neck section with the circular portion 16 of the support and thereafter maintaining the section 17 in contact with 50 and parallel to section 15 until a lock ring 20 is slipped longitudinally along the section 17 into the position shown in the figure in the drawing. The ring 20 will then hold the members 15 and 55 17 in correct assembly. Normally section 17 has a tendency to spring away from section 15.

In this manner, the support 13 is firmly secured into position on bottle 10 but such support 13 may readily be removed by sliding the ring 20 along horizontal sections 15 and 17 until clear of section 17 whereupon the circular section 16 will open sufficiently with the urge of the hand to allow the separation of the bottle 10 from the support 13.

Suspended from the hook section 19 is a sign 21 which may be of cardboard or similar material. Sign 21 has an aperture 22 adjacent its top. A rubber band 23 is slipped through the aperture 22 and a loop is formed in the band by inserting one end of such band at one side of sign 21 through the other end of such band at the other side of said sign. The inserted end of the band 23 is suspended upon the hook 19.

The height of vertical section 14 of the support 13 is in excess of the length of the sign 21 and the suspending section of the rubber band 23 so 20 that the bottom edge of the sign 21 does not contact the flange 12 of the bottle 10 or any cover member that may be disposed thereon. Sign 21 may be supplied with advertising material on 25 both its front and rear sides.

The assembly of the bottle, support, sign and band is clear from the description which has been given and from the figure of the drawing. When it is desired to put a sign upon a bottle, the support 13 is attached in the manner heretofore described, a band is attached to the sign 21 in the manner herein set out, and the loop of the rubber band is seated upon the hook section 19.

Band 23 provides a resilient support for the sign 21. If the sign is given a manual twist or rotation, it will continue to rotate first in one direction and in the other for a long period of time upon the momentum thus obtained for it. The band 23 twists and untwists during this 35 operation. The slightest breeze or draft of air will make the sign 21 rotate or move and thus attract much attention. The sign 21 is substantially animated although no means for animation is 40 provided.

The length of horizontal sections 15 and 18 of the support are such that the sign 21, when rotating, will not contact the upright section 14 of the support 13 but will clear the support. The 50 hook 19 at its lowermost portion should be substantially axial with the axis of the bottle 10 for best results.

The support and sign may assume many other shapes different from these shown without depart- 55

ing from the spirit of the invention set out in the appended claims.

What is claimed as new and is desired to be secured by Letters Patent of the United States is:

- 5 1. A standard for supporting a sign in association with an article of merchandise, comprising a wire having a hook section, an upright section, a lower horizontal section, said lower horizontal section being in the form of two straight sections with a loop therebetween adapted to encircle a portion of said article, and means for securing said straight sections in selected relation to one another to clamp the loop section about the article.
- 10 15 2. A standard for supporting a sign in association with an article of merchandise, comprising a length of wire having two lower horizontal sections and a loop section therebetween, said horizontal sections normally being obliquely angularly spaced and said loop section being shaped

20 to surround a portion of such article, a vertical section, and an upper horizontal section terminating in a hook having its lowermost part in alignment with the axis of such article, and a ring removable from one horizontal section and slideable along said lower horizontal sections to secure them in substantial parallelism while said loop section is about such portion of said article.

3. A standard for supporting a sign in association with an article of merchandise comprising a single, continuous length of wire having a hook section, an upright section and a supporting section, said hook being adapted for suspending the sign and the supporting section, having a loop portion for engaging the article and a free end of substantial length extending therebeyond and adapted to be interlocked with said supporting section for securing said standard to said article.

FLOYD R. PERKINS. 20
